(57) **CLAIM**

The ornamental design for a solid loop lifter for concrete structures, as shown and described.

DESCRIPTION

FIG. 1 is a front isometric view of a solid loop lifter for concrete structures embodying my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent the shaded areas represent the bounds of the claim and all other broken lines are for illustrative purposes only. None of the broken lines form part of the claimed design.
